UNITED STATES PATENT OFFICE.

JOHN F. MILLS, JR., AND CHARLES FREMD, JR., OF PORT CHESTER,
NEW YORK.

MAIL CATCHER AND DELIVERER.

SPECIFICATION forming part of Letters Patent No. 694,878, dated March 4, 1902.

Application filed May 16, 1901. Serial No. 60,331. (No model.)

To all whom it may concern:

Be it known that we, JOHN F. MILLS, Jr., and CHARLES FREMD, Jr., citizens of the United States, and residents of Port Chester, in the county of Westchester and State of New York, have invented a new and Improved Mail Catcher and Deliverer, of which the following is a full, clear, and exact description.

10 The purpose of the invention is to provide a device adapted for attachment to the door-section of a mail-car and a corresponding device to be located upon a platform of a station adjacent to the tracks, each of which devices is fitted with means for holding a mail-bag in suspension and means for catching and gripping a mail-bag, the arrangement of the holding and gripping devices being such that the device upon the platform will automatically take the suspended bag from the mail-car at the same time that the gripping device carried by the mail-car takes the suspended bag from the platform device.

15 A further purpose of the invention is to provide safe and automatically-acting gripping devices for the mail-bags so constructed that said devices may be set in an open position and the moment that a bag is brought into engagement with the open devices gripping-arms, forming portions of such devices, will instantly close over the bag and hold it until purposely released, and, further, to so construct the platform device that when a bag is gripped thereby the gripping mechanism will 20 be automatically caused to turn to a position practically parallel with the track or a position over the platform to which the device is attached, from which position the gripping device may be readily released and permitted 25 to return to a position at right angles to the track or in a position to receive a bag from a mail-car.

The invention consists in the novel construction and combination of the several parts, as will be hereinafter fully set forth, and pointed out in the claims.

30 Reference is to be had to the accompanying drawings, forming a part of this specification, in which similar characters of reference indicate corresponding parts in all the figures.

Figure 1 is a perspective view of a portion of

a mail-car and the improved device applied thereto and a perspective view of the device applied to a platform adjacent to the track, showing the gripping-sections of both devices in 55 open position. Fig. 2 is an enlarged front elevation of the upper portion of the platform device in closed position, parts being in section. Fig. 3 is a partial side elevation and sectional view of the device adapted for attachment to 60 a mail-car. Fig. 4 is a vertical section through the device shown in Fig. 3, illustrating a mail-bag gripped by the jaws of the device. Fig. 5 is a horizontal section through a portion of a mail-car and supporting-shaft of the device 65 and a plan view of the gripping mechanism in open and set position, and Fig. 6 is a horizontal section through the standard or post of a slightly-modified form of the device and a plan view of the gripping mechanism shown 70 in positive lines as closed upon a bag and in dotted lines as in open position.

A represents a portion of a mail-car having the usual side door-opening 10. Adjacent to one of the side jambs of the door-opening 10 75 a shaft 11 is mounted to turn in bearings 12 at the upper portion of the door-opening or at the roof of the car and in corresponding bearings which are secured to the floor of the car. This shaft 11 is provided at its upper 80 portion with a spring 13, coiled around the shaft, and one end of the spring is secured to the shaft, while the other has bearing against and is secured to the jamb adjacent to which the shaft 11 is placed, and the tendency of 85 this spring is to turn the shaft 11 in an outward direction; but such action on the part of the spring may be restrained by means of a brake 14, consisting of an arm pivoted upon a suitable bearing 15, attached to the upper 90 portion of the door-opening and having a fork at its lower end which embraces the shaft, as shown in Fig. 3; but the brake 14 may be removed from the shaft 11 at any time by drawing down upon a rod, link, cord, 95 or chain 16, attached to the said brake-lever. Two arms 17 are secured to the shaft 11 at right angles thereto, and these arms are in a horizontal position and are constructed in the conventional way to hold a mail-bag 18 in 100 such manner that the mail-bag may be readily slipped from said arms and when the

spring 13 on the shaft 11 is in action the arms 17 extend out from the mail-car, at a right angle thereto, as is shown in Fig. 1. Below the arms 17 other arms 19 and 20 are secured to the shaft 11, occupying a position similar to the arms 17, and each arm 19 and 20 is provided with a jaw, (designated, respectively, as 19^a and 20^a,) which jaws are curved in direction of the door-opening 10, as is shown in Fig. 1. A third jaw 21 is secured upon a spindle 22^a, which extends from the arm 19 to the arm 20, where the jaws 19^a and 20^a connect with said arms, and an intermediate jaw 22 is adapted when in set position to face oppositely to the jaws 19^a and 20^a, and all of the jaws are more or less curved and are preferably serrated or roughened upon their inner faces. A spring 23 is coiled around the spindle 22^a, and this spring is attached at one end to the spindle and at the other end to a collar 21^a, which extends upward from the lower arm 20, as is best shown in Fig. 3. A keeper-arm 24 is secured to the spindle 22^a at a point above the intermediate jaw 22, and this keeper-arm extends rearward and then outward or forward between the upper fixed jaw 19^a and the intermediate movable jaw 22. This keeper-arm 24 is adapted for engagement by a latch-head 25 when the intermediate or movable jaw is to be held in set or open position, as shown in Fig. 3. Said latch-head 25 is attached to an angular trip-bar 26, which is fulcrumed upon the upper fixed jaw 19^a and extends downward in front of the lower fixed jaw 20^a to a point below the same, and this trip-bar 26 is preferably provided with curved cross-bars 27, arranged at intervals in its length. When the shaft 11 is relieved from the brake 14, the said shaft turns outward, and the arms 19 and 20 extend outward at right angles to the mail-car; but before the shaft 11 is released from the brake 14 the movable jaw 22 is drawn inward to such an extent that the latch-head 25 may engage with the keeper-bar 24 and hold the movable jaw in its set position, placing the spring 23 under tension. When the latch-head 25 is thus in engagement with the keeper-bar 24, the trip-bar 26 will be out of engagement with 50 and will extend outward from the concaved or inner face of the lower fixed jaw 20^a, and as soon as a mail-bag is brought in engagement with the trip-bar 26 the said bar is forced back and the latch-head 25 is disengaged from the keeper-bar 24, thus freeing the movable jaw 22, which, owing to the spring 23, will instantly close over the bag and hold said bag between it and the fixed jaws and the trip-bar. The shaft 11 may then be turned inward, so as to bring the gripped mail-bag within reach of the operators in the mail-car, and when the movable jaw 22 is opened it is again set and the mail-bag is freed.

In connection with the device applied to the main car an equivalent device is adapted to be placed upon a platform at a station adjacent to the tracks over which the mail-car is

to pass. This latter device consists of an upright or standard B of any approved type, provided with a head or cap section B', which is mounted to turn upon the upper portion of the standard or upright B through the medium of a pin 28, carried by either one or the other of the said parts, and the opposing surfaces of the two parts B and B' are chambered to receive a spring 29, coiled around the pin 28, one end of which spring is attached to the cap-section B' of the upright or standard and the other end of the spring is attached to the body portion of the standard or upright. The cap-section B' of the upright or standard is usually provided with an exterior flange or shoulder 30 at its body portion engaged by a projection 32 from an arm or bracket 31, attached to the body B of said upright or standard, although the two parts may be held together in any other approved manner. A latch 33 is pivoted on the upper portion of the bracket 31, and a chain, rope, or link 34 or its equivalent is attached to this latch, so that the latch-head may be drawn downward whenever it is desired to permit the jaws, to be hereinafter described, to be brought in position at right angles to the track or in position to receive a mail-bag which is carried by the horizontal retaining-arms 17, forming a portion of the device, located in the mail-car.

The gripping mechanism for the mail-bag is practically the same as that which has been described as carried by the mail-car and is attached to the cap or head B'. This gripping mechanism consists of an upper arm 35, secured to the cap or head B', terminating in a curved jaw 36 at its outer end, and a lower parallel arm 37, also attached to the cap or head B', terminating at its outer end in a curved jaw 38, parallel with the jaw 36. A spring-controlled pin 39, corresponding to the pin or spindle 22^a, heretofore described, is passed from the arm 35 to the arm 37, and on this pin or spindle 39 a jaw 40 is secured, curved oppositely to the jaws 36 and 38 and adapted to move to and from the space between them. A keeper-bar 41 is secured also to the spindle or pin 39, corresponding to the keeper-bar 24, hereinbefore described. This keeper-bar 41, when the spring-controlled movable jaw 40 is in open position, is engaged by a latch-head 42, corresponding to the latch-head 25, hereinbefore described, and this latch-head is carried by a trip-lever 43, fulcrumed upon the upper jaw 36 and extending downward in front of and below the lower jaw 38, being provided with curved cross-bars 44. The lever 43 corresponds to the lever 26, heretofore described, and when this lever 43 is pushed inward by the mail-bag coming in contact therewith the latch-head 42 is released from the keeper-bar 41 and the movable jaw 40 closes over the bag, clamping the bag to the fixed jaws 36 and 38. The spring 29 tends to carry the gripping mechanism at a right angle to the track or to the mail-car, as shown in Fig. 1, and when the mail-bag is caught

between the jaws 36, 38, and 40 the force of contact carries the jaws and the cap B' of the upright or standard around parallel with the rails, and the arms carrying the fixed jaws 5 are then held in that position by the latch 33, which automatically engages with the lower arm 37, as shown in Fig. 2. The jaw 40 is then opened, causing the keeper-bar 41 to again engage with the latch-head 42, and the 10 gripping device is held in its position parallel to the track until such time as it is to be called into action, whereupon by drawing down on the link or chain 34 the latch 33 is disengaged from the gripping mechanism and 15 the spring 29 carries the gripping mechanism to its receiving position at right angles to the track and to the car passing over said track. The body of the standard or upright is provided with horizontal arms 45, which extend 20 at right angles to the track and are fitted to hold a mail-bag at the top and at the bottom, the arms 45 corresponding to the arms 17 described in connection with the mail-car.

In Fig. 6 we have illustrated a slight departure in the construction of the device which is to be placed on the platform and which is to receive the mail-bag from a passing train. This modification consists of an upright or standard 46, having a cap 46^a, regulated by a spring corresponding to that shown and described with reference to Fig. 2, and from the cap 46^a of the standard or upright 46 fixed arms 48 are extended, each arm terminating at its outer end in a jaw 48^a. A 35 pin or spindle 49 is passed through these arms 48, corresponding to the spindles 22^a and 39, heretofore described, and on this spindle a jaw 50 is secured, which is curved oppositely to the jaws 48^a, and on the same spindle 49 40 a keeper-bar 51 is secured, corresponding to the keeper-bars hereinbefore described and adapted for engagement with a latch-head 52 when the jaw 50 is in open position. The latch-head 52 is attached to a trip-lever 53, corresponding to the levers 26 and 43, already 45 described; but the spindle 49 also carries a curved arm 54 below the keeper-bar 51, and this curved arm is provided with a roller 55 at its outer end. The upright 46 is provided 50 with a rear horizontal arm 47, shaped on the lines of a compound curve. The jaw 50 being in its open position, as soon as the mail-bag strikes the trip-lever 53 said jaw 50 is closed upon the bag, moving in direction of 55 the jaws 48^a, and the force will carry the arms 48 in direction of the curved arm 47, and the roller 55 on the rearwardly-extending arm

54 will strike the curved arm 47 from the standard or upright and will open the jaw 50 and cause the keeper-bar 51 to again engage 60 with the latch-head 52, as is shown in dotted lines in Fig. 6. The arms 48 will then be returned by the spring controlling the head of the upright or standard to their normal position or to a position which will enable the 65 jaws 48^a and 50 to receive another mail-bag.

Having thus described our invention, we claim as new and desire to secure by Letters Patent—

1. In mail-bag catchers and deliverers, a 70 spring-controlled support mounted for rocking movement, arms extending from the said support, curved jaws carried by said arms, an oppositely curved jaw mounted between the said arms for movement to and from the 75 fixed jaws, a keeper carried by the movable jaw, and a latch for the said keeper carried by a fixed jaw, the latch being released from the keeper by an object brought in contact therewith, for the purpose described. 80

2. In a mail-bag catcher and deliverer, a spring-controlled rocking support, arms fixed to the said support, terminating in curved jaws, a spring-controlled jaw mounted for movement between the said arms, the movable jaw being curved oppositely to the fixed 85 jaws, a keeper-bar connected with the movable jaw, and a latch connected with one of the fixed jaws, adapted for engagement with the said keeper-bar, which latch extends 90 downward in front of the concaved portions of the fixed jaws, for the purpose described.

3. In a mail-bag catcher and deliverer, a spring-controlled rocking support, arms fixed to the said support, extending horizontally 95 therefrom and terminating in curved jaws, an oppositely curved jaw, spring-controlled and mounted to rock between the said arms, to and from the fixed jaws, a keeper-bar connected with the said movable jaw, a latch 100 carried by one of the fixed jaws, adapted for engagement with the keeper-bar, and extending down in front of the curved, concaved faces of the said fixed jaws, and a latch for the said arms, as and for the purpose described. 105

In testimony whereof we have signed our names to this specification in the presence of two subscribing witnesses.

JOHN F. MILLS, JR.
